UNITED STATES PATENT OFFICE

2,663,997

DRAINAGE TUBE

Otto W. Schmidt, Kansas City, Kans., and
William C. Martin, Wooster, Ohio

Application September 22, 1947, Serial No. 775,486

4 Claims. (Cl. 61—11)

1

This invention relates to new and useful improvements in drainage tubes, and has for its principal object the provision of a specially constructed drainage tube having inlet openings protected in such a manner as to prevent the entry of sand or silt to said tube while admitting liquid thereto.

Another object is the provision of a drainage tube formed to present passageways for the entry of fluid, the outer ends of said passageways being disposed below the inner ends thereof, thereby necessitating that fluid rise to enter said tube.

Another object is the provision of a drainage tube having inlet ports formed adjacent the upper portion thereof, and being formed to present members overhanging and extending below said inlet ports.

Still another object is the provision of a drainage tube comprising a channel and a cover member extending outwardly beyond the edges of said channel and forming passageways in combination with said channel through which fluid must rise to enter said tube.

Other objects are simplicity and economy of construction, and adaptability of the parts when disassembled to be nested compactly for economical storage and shipping.

With these objects in view, as well as other objects which will appear in the course of the specification, reference will be had to the drawings, wherein:

Figure 1 is a vertical section adjacent the curb of a street, showing a street drainage system employing a drainage tube embodying the present invention.

Fig. 2 is a plan view of a drainage tube embodying the present invention.

Fig. 3 is a fragmentary section taken on line III—III of Fig. 2.

Fig. 4 is an enlarged transverse section taken on line IV—IV of Fig. 2.

Fig. 5 is an enlarged transverse section taken on line V—V of Fig. 2.

Fig. 6 is an end view of a plurality of the channel portions of the tube, nested for shipping or storage.

Fig. 7 is an end view of a plurality of the cover portions of the tube, nested for shipping or storage.

Fig. 8 is a transverse cross-sectional view of a modified form of the tube wherein the tube is formed of a single sheet of metal.

Fig. 9 is an inverted plan view of the tube shown in Fig. 8.

2

Fig. 10 is a transverse cross-sectional view of another modified form of the tube wherein the channel and cover portions are joined by the resilient engagement of the parts.

Fig. 11 is an inverted plan view of the tube shown in Fig. 10.

Like reference numerals apply to similar parts throughout the several views, and the numeral 18 refers to a drainage tube comprising a channel 18 of any desired cross-section, the edges of said channels being bent to form outwardly and downwardly extending flanges 20, and a transversely corrugated cover member 22 having its edge portions turned downwardly so that the bottom edges of the corrugations lie against flanges 20, and so that the under valleys 24 thereof form passageways 26 in combination with said flanges. It will be noted that cover members 22 extend outwardly past the outer edges of flanges 20, thus providing an overhang protecting the outer ends of passageways 26 and preventing the direct packing of earth or sand in said openings. Cover members 22 are preferably laterally arched as shown in Figs. 4 and 5 for greater strength.

As is seen in Figs. 6 and 7, channels 18 and cover members 22, when disassembled, may be compactly nested for economical use of space in shipping and storage. In assembly, tabs 28 struck from flanges 20 at spaced intervals therealong, said tabs being left in the flat during storage, are projected through cover member 22 and bent over to secure said cover member clamping to said flanges. It is contemplated that sections of said tubing shall be butted together and secured against relative movement by the following means. The cover member 22 is spaced apart from the ends of channel 18 as shown in Fig. 3, so that when the channels are in abutted relation as shown, the ends of the adjacent cover members will be spaced apart. A two-piece band connector 30 comprises a U-shaped member 32 having outwardly turned ears 34 and adapted to overlap the joint between the channels with the ears 34 resting against the flanges 20, and a corrugated strip 36 adapted to overlap adjacent cover members and to extend across the space therebetween. The corrugations of strip 36 are adapted to register with corresponding corrugations of cover members 22, so that when screws 38 are inserted to join the end portions of strip 36 and U-shaped member 32, as shown in Fig. 7, the abutted tubes will be rigidly retained in aligned relation.

As is plainly shown in Figs. 4 and 5, when the tube is buried the outer or inlet ends of passageways 26 are disposed below the inner ends, and

consequently fluid must rise through said passageways. Since the velocity of flow through said passageways is ordinarily low, sand, dirt, silt, etc. entrained in the fluid is allowed to settle out and only relatively clean fluid is allowed to enter the tube. In ordinary drainage tubes without inlets so disposed, sand and silt enter the tube freely, and in a comparatively short time the tube may become so full as to be virtually useless. Thus the usefulness of the tube is greatly increased.

One application of the drainage tube is illustrated in Fig. 1, showing a transverse cross section at the curb line of a street. A trench 40 is dug along the curb line, a drainage tube 16 laid along the bottom thereof, and the trench filled with loosely packed material 41, such as sand, gravel, or the like. The curbing 42 is supported on said sand, the footing 44 thereof being narrower than the trench. The paving slab 45 is spaced apart from the curbing at 46 to permit water draining from the slab to flow into the sand 41. Water draining through the soil between the curbing and sidewalk 50 also enters the sand. The water then flows through the sand by gravity, enters tube 16 as previously described, and is conducted thereby to any point desired.

In the modified form shown in Figs. 8 and 9, the drainage tube 52 is formed of a single sheet of metal, the opposite edges thereof being bent to form abutting flanges 54 joined by any suitable means such as by rivets 56. Said tube is formed to present outwardly and downwardly extending lips 58 at its opposite upper edges. A plurality of holes 60 are formed through the inner face of said lips adjacent the juncture of said lips with the channel portion 62 of the tube. The operation is substantially identical to that of the preferred form, water being required to rise from the lower edges of lips 58 to the level of holes 60 before entering the tube. Holes 60 are spaced at regular intervals along the length of the lips.

In the modified form shown in Figs. 10 and 11, the drainage tube 64 is comprised of a channel 66 having outwardly turned flanges 68 along its edges, and a cover member 70 having inwardly opening grooves 72 formed adjacent its edges to receive flanges 68, and being provided with downwardly extending flanges 74 spaced apart from the channel 66. Flanges 68 are provided with a plurality of longitudinally spaced apart holes 76. As featured in the previously described forms, water must rise from the lower edges of flanges 74 to the level of holes 76 before it may enter

the tube. Cover 70 and channel 66 may be assembled by sliding them together longitudinally, or by resiliently compressing the channel until flanges 68 thereof will snap into grooves 72 of the cover.

What we claim as new is:

1. A drainage tube comprising a sheet metal channel having outwardly and downwardly extending flanges at its upper edges, and a cover member all portions on a transverse line of which slope downwardly from the center line thereof and having depending side portions secured in spaced relation to said flanges whereby openings to said channel are formed between said cover member and said flanges, said openings sloping upwardly to enter said channel.

2. A drainage tube comprising a sheet metal channel having outwardly and downwardly extending flanges at its upper edges, and a continuously transversely arched cover member having continuous transverse corrugations secured to said flanges to form upwardly sloping tubular openings to said channel, said cover member extending outwardly and downwardly beyond the edges of said flanges to form an overhang protecting the entrances to said openings.

3. A drainage tube comprising a sheet metal channel having outwardly and downwardly turned flanges at its upper edges, and a cover member continuously convex from edge to edge and having continuous transverse corrugations secured to said flanges; said cover member and flanges being spaced apart at intervals to provide upwardly sloping tubular openings to said channel.

4. A drainage tube comprising a sheet metal channel having outwardly and downwardly turned flanges at its upper edges, and a transversely corrugated cover member formed continuously convexly from edge to edge secured to said flanges thereby to form upwardly sloping tubular passageways to said channels, said cover extending outwardly and downwardly beyond the outer edges of said flanges to form an overhang protecting the outer entrances of said passageways.
